(57) **CLAIM**

The ornamental design for a drawer face, as shown and described.

DESCRIPTION

This application claims priority to U.S. Design Patent Application No. 29/196,713, (filed Jan. 2, 2004).

FIG. 1 is a front elevational view of a first embodiment of a drawer face according to my new design;

FIG. 2 is a rear elevational view of the drawer face shown in FIG. 1;

FIG. 3 is a left side elevational view of of the drawer face shown in FIG. 1;

FIG. 4 is a right side elevational view of of the drawer face shown in FIG. 1;

FIG. 5 is a top plan view of of the drawer face shown in FIG. 1;

FIG. 6 is a bottom plan view of of the drawer face shown in FIG. 1;

FIG. 7 is a perspective view of of the drawer face shown in FIG. 1;

FIG. 8 is a front elevational view of a second embodiment of a drawer face according to my new design;

FIG. 9 is a rear elevational view of the drawer face shown in FIG. 8;

FIG. 10 is a left side elevational view of the drawer face shown in FIG. 8;

FIG. 11 is a right side elevational view of the drawer face shown in FIG. 8;

FIG. 12 is a top plan view of the drawer face shown in FIG. 8;

FIG. 13 is a bottom plan view of the drawer face shown in FIG. 8;

FIG. 14 is a perspective view of the drawer face according shown in FIG. 8;

FIG. 15 is a front elevational view of a third embodiment of a drawer face according to my new design;

FIG. 16 is a rear elevational view of the drawer face shown in FIG. 15;

FIG. 17 is a left side elevational view of the drawer face shown in FIG. 15;

FIG. 18 is a right side elevational view of the drawer face shown in FIG. 15;

FIG. 19 is a top plan view of the drawer face shown in FIG. 15;

FIG. 20 is a bottom plan view of the drawer face shown in FIG. 15; and,

FIG. 21 is a perspective view of the drawer face shown in FIG. 15.

The broken lines shown are for illustrative purposes only and form no part of the claimed design.
